UNITED STATES PATENT OFFICE.

PAUL H. GRIMM, OF GLEN COVE, NEW YORK, ASSIGNOR TO THE GLEN COVE MANUFACTURING COMPANY, OF SAME PLACE.

APPARATUS FOR DRYING STARCH REFUSE, &c.

SPECIFICATION forming part of Letters Patent No. 440,262, dated November 11, 1890.

Application filed July 5, 1888. Serial No. 279,004. (No model.)

To all whom it may concern:

Be it known that I, PAUL H. GRIMM, of Glen Cove, in the county of Queens and State of New York, have invented a new and useful Improvement in Apparatus for Drying Starch Refuse and other Substances, of which the following is a specification, reference being had to the accompanying drawings.

My invention relates to apparatus for drying solid or granular materials, more particularly starch refuse, in which the drying chamber or kiln is provided with a succession of floors—one above another—formed of tilting floor-sections.

I will now proceed to describe the improvement, and point out its novel features in claims.

In the drawings, Figure 1 represents a vertical longitudinal sectional view of a drying apparatus embodying my improvement and showing the interior of a drying-chamber or kiln; Fig. 2, a transverse vertical sectional view of Fig. 1; Fig. 3, a longitudinal vertical sectional view of the same apparatus, showing the interior of an air-heating chamber. Fig. 4 represents a longitudinal sectional view of a perforated tilting floor-section, a tilting arm and rod, and a steam-heating pipe, to which the floor-section is pivoted; Fig. 5, a transverse vertical section corresponding with Fig. 4. Fig. 6 represents a plan view of a reticulated tilting floor-section. Fig. 7 represents a longitudinal sectional view of a barred or grated tilting floor-section, and Fig. 8 a plan view of Fig. 7.

Like letters of reference indicate corresponding parts in all the figures.

C C indicate a series of drying-chambers or kilns arranged side by side and having floors one above another, upon which the material to be dried is placed, and having steam-heating pipes beneath or between the several floors.

A A indicate the steam-heating pipes, and B B the tilting floor-sections pivoted thereto, there being represented one straight pipe for each floor-section, and the pipes being immediately beneath their respective floor-sections, and consequently in close proximity to the material to be heated or dried, and the heat

of the pipe is thereby more fully utilized and more effective than if otherwise applied.

To still further insure the direct and indirect application to the material of the heat from the steam-pipes, the tilting floor-sections 55 may be barred or grated, perforated or reticulated—as, for example, as represented in Figs. 4, 5, 6, 7, and 8. Figs. 4 and 5 represent a floor-section consisting of frame a, covered with a sheet b of perforated metal; Fig. 6, a similar frame a', covered with a sheet b' of wire cloth or netting; and Figs. 7 and 8, a grated or barred floor-section formed of a frame a², parallel bars or rods b², such as may be formed by sawing numerous parallel cuts 65 through a floor plank or board, the parts between the cuts forming the bars b³ of such barred or grated floor-section.

c c designate connecting-pipes outside of the drying-chambers C, through which the 70 steam-heating pipes communicate with each other. Said connecting-pipes c c are represented as contained in an air-heating chamber or passage D, consisting of the space between the side of the drying-chamber and an 75 outer wall or casing E.

F represents an air-circulating device—in this example a fan or blower—interposed between said drying-chamber C and the air-heating chamber or passage D for exhausting 80 the air from the latter and forcing it into the former.

In order to form an air-passage at one end of each floor on the side of the heating-chamber opposite to that of the air-passage through 85 the floor next above or below it, whereby the air in its upward passage will be caused to flow alternately from one side to the other of the heating-chamber or kiln, the pipe of each floor-section is represented as located directly 90 opposite the edges of the floor-sections next above or below it—that is to say, directly opposite the middle of the space between the nearest pipes of the floors above or below.

G G indicate feed-hoppers, situated at one 95 end or one side of and above the top floor of each chamber C to deliver the moist starch refuse or other material upon that end of the floor.

H H indicate endless chains of slats or 100

sweeps above and parallel with the top floors for spreading the moist material supplied by the hoppers evenly upon said floors.

I indicates the inlet-pipe, from which steam flows into the pipes A of the upper floor, each of said pipes A having a separate connection therewith and discharging at the opposite end into a connection-pipe c, communicating with a pipe A of the floor below, which in turn discharges through a second connecting-pipe c into a pipe A of the next lower floor, and so on to the lowest floor, the pipes A of which communicate with the outlet-pipe J. In this manner each opening in the inlet-pipe is connected by one continuous pipe with the corresponding opening into the outlet-pipe, said continuous pipe consisting of one pipe A in each floor and the several connecting-pipes, whereby the said pipes of each floor communicate one with another.

K K designate division-plates or partitions extending from opposite sides alternately of the air-heating chamber or passage D part way across the same, whereby the air flowing through the passage may be conducted or deflected alternately from one side to the other of the passage D. Every part of the air flowing through the passage will thus be brought repeatedly in contact with the heated connecting-pipes.

In the example of my improved apparatus represented in the drawings the drying chambers or kilns are placed side by side, forming a series of four chambers. The inner or partition walls may be formed of wooden studding or frames d and sheet-iron sheathing e; or the walls and partitions may be constructed entirely of either iron or wood. If of the latter, the holes for the passage of pipes should be shielded with iron. The several drying-chambers are open at the top for the free escape of the vapors and air. Below they all open into a single hopper-shaped receptacle L, into which the dried material is dumped from the lower floors, and from which it is driven off through a discharge-opening f. All the drying-chambers C of the series have a common inlet-pipe I and a common outlet-pipe J, located at the top and bottom, respectively, and on the same side of the series. Each steam - heating pipe extends directly through the four drying-chambers, the air-heating chambers being two in number only, one on each side of the series.

g g designate the flanges by which the pipes A are connected to the outlet and inlet pipes.

h h designate the flanges of the inlet and outlet pipes.

M M designate cold-air-inlet pipes, through which air enters the air-heating chambers; and F, an air-blower or fan, by which the heated air is exhausted through passages N' from the air-heating chambers D and discharged into the hot-air pipe O through a pipe O'.

i i are hot-air-inlet nozzles, through which the heated air from the pipe O enters the drying-chambers.

The endless chains of slats or sweeps H H are represented as carried by chain-wheels j j, fixed on a driving-shaft k, and a driven shaft l parallel therewith. On the overhanging end of the driving-shaft k a chain-wheel j' is represented, to which power may be applied. The slats or sweeps m may be of wood or metal and attached to endless chains n.

P designates tilting rods or levers placed transversely to the tilting floor-sections and below them, to which the tilting-arms o are pivotally attached. A tilting-rod P will be required to each floor; but they are not all represented in the figures.

p p designate handles to the tilting-rods, projecting through the end wall of the chambers to be grasped by the hand, to be pulled or pushed in or out to dump the tilting sections or return them to the horizontal position. It will be seen that the handles p for the tilting-rods P extend alternately upon opposite sides of the heating-chamber. By this means it will be readily seen that when, for instance, the upper of the handles p is drawn outwardly the floor-section with which it operates will be tilted so as to dump the material downwardly and at an angle upon the next floor below, the angular direction in which the material is dumped being toward the right of Fig. 1. When, on the contrary, the material is to be dumped from the floor which just received it, and the handle p to the right of Fig. 1 is withdrawn, the floor-section will be tilted in such manner as to dump the material downwardly upon the next floor and in an angular direction toward the left of Fig. 1. By this alternate means of dumping the material first toward the right and then toward the left, or conversely, an important advantage is secured, in that accumulations of material upon one side of the chamber in heaps is avoided, which would not be the case were all the floor-sections dumped in one direction. This is also advantageous because it admits of such an arrangement of the floor-sections that openings will be left at different ends of adjacent floor-sections, in order that the upwardly-passing current of air and vapor may pursue a circuitous course. The levers or rods P may or may not project through the wall. In the latter case a hand hole or opening may be made in the wall or casing of the chamber and the hand may reach inside and grasp the lever therein, and after the contents of the floor is dumped the hand may be withdrawn and the hand-hole closed.

The operation of my improved drying apparatus may be continuous. The moist or wet starch refuse or other material to be dried enters at the top and drops out, when thoroughly dried, at the bottom. The bottom floor, when the material thereon is dry enough, is dumped first, and the floor next above is dumped onto it, and so on to the top. Whenever the top floor is dumped onto the floor below it, fresh material may be immediately spread upon the said upper floor.

What I claim as new, and desire to secure by Letters Patent, is—

1. The combination, with a drying-chamber and a vertical series of intercommunicating compartments within the chamber, of air-chambers located at the opposite ends of the drying-chamber, the air-chambers communicating with the outside air at their upper portions and with the drying-chamber at their lower portions, steam-pipes extending back and forth along the floors of the several compartments of the drying-chambers and projecting into the air-chambers at the ends of the drying-chamber, and a force-draft device arranged to draw the air from the lower portions of the air-chambers and discharge it into the lower portion of the drying-chamber, substantially as set forth.

2. The combination, with a drying-chamber, a vertical series of floor-sections, steam-pipes

arranged in staggered order and forming supports for the floor-sections, and air-chambers located at the opposite ends of the drying-chamber, said air-chambers communicating with the outside air at their upper portions and with the drying-chamber at their lower portions, of steam-pipe connections located within the air-chambers, each pipe-section connecting a section of steam-pipe with another section of the same pipe located obliquely above or below it, division-plates located at intervals within the air-chambers, and a force-draft apparatus drawing air from the lower portion of the air-chambers and discharging it into the drying-chamber, substantially as set forth.

PAUL H. GRIMM.
